UNITED STATES PATENT OFFICE.

HARRY D. HEWETT, OF PROVIDENCE, RHODE ISLAND, ASSIGNOR TO
UNITED SILK MANUFACTURING CO., OF PROVIDENCE, RHODE
ISLAND, A CORPORATION OF RHODE ISLAND.

WOVEN FABRIC.

SPECIFICATION forming part of Letters Patent No. 793,524, dated June 27, 1905.

Application filed June 11, 1904. Serial No. 212,203.

To all whom it may concern:

Be it known that I, HARRY D. HEWETT, a citizen of the United States, residing at 39 Charles street, Providence, in the county of Providence and State of Rhode Island, have invented new and useful Improvements in Woven Fabrics, of which the following is a specification.

This invention is an improved woven fabric with woven tucks, and it is characterized particularly by a woven backing which prevents the tucks from drawing or pulling out. The tucks produced are as strong or stronger than those made from flat cloth, and the fabric is particularly suitable for dressmaking.

15 The fabric is in the main one-ply; but the warp-threads are divided into three sets. In the body of the fabric these three sets all take the same weft; but at the tucks one set is looped and takes the weft of the tuck and the second 20 and third sets are divided to each take separate weft-threads, forming under the tucks a two-ply fabric or backing, which prevents the tucks from drawing or pulling out, and after 25 passing the tuck all the sets of warp-threads are merged into one-ply.

In the accompanying drawings, Figure 1 is a plan view of the fabric. Fig. 2 is a sectional diagram greatly enlarged. Fig. 3 is a diagram in plan, the tuck being indicated as 30 cut off on the line 3 3 of Fig. 2.

Referring specifically to the drawings, three sets of warp-threads are indicated, respectively, at *a*, *b*, and *c*, and the weft-threads are indicated by the numerals 1 to 21 for the purpose of illustration. The tuck is indicated at *D*, and the weft-threads of the tuck are indicated at *d*. The body *A* of the fabric is indicated in the diagrammatic view taking the weft-threads 1 to 4 and 16 to 21, said body being formed 35 in the ordinary manner. The warp-threads *a* form a backing under the tuck. The warp-threads *c* are looped to form the tuck, and the warp-threads *b* are woven with the threads *c* to form a rib or binding layer *C* at the foot 40 of the tuck. In producing the tuck and the rib referred to the proper loom mechanism is employed, and the warp-threads are first sepa-

rated into two sheds, one being formed by the warp-threads *a*, producing the backing, and the other by threads *b* and *c*, producing the 50 rib referred to. The two latter sets of threads are further separated, and the threads *c* are looped to produce the tuck, the weft *d* being woven therein. The warp-threads *a* and the 55 weft woven therein produce a continuous woven fabric throughout the length of the piece of goods and, in connection with the warp-threads *b*, serve to sustain whatever pressure or weight may be applied to the goods without danger of drawing, the woven portion producing the rib referred to and formed by the warp-threads *b* and *c*, and the weft-threads (indicated at 5, 7, 9, 11, 13, and 15) also assist in preventing the drawing of the tuck-threads by providing a woven portion 60 between the foot of the tuck and the body of the fabric, affording two layers or a two-ply fabric, which effectively prevents any drawing of the threads forming the tuck and also adds greatly to the ornamental features of the 65 cloth. By appropriate loom mechanism the tucks and the spaces therebetween can be made any width desired and can be woven in 70 one or more colors.

It is known that woven-tuck fabrics have 75 been heretofore produced, but such tucks have been formed in one-ply fabrics without a continuous woven portion extending across or spanning the base of the tuck, and consequently the warp-threads of such tucks would 80 draw under a slight pull or strain, which is objectionable. In the fabric herein disclosed this defect is remedied, since strain on the fabric is not communicated to the warp-threads of the tuck, but is sustained by the 85 other warp-threads.

What I claim as new, and desire to secure by Letters Patent, is—

1. A tucked woven fabric having part of its warp-threads looped to form the tuck, and having two continuous woven plies extending under the tuck and one ply between the tucks. 90
2. A tucked woven fabric having three sets of warp-threads woven into one ply between

tucks, one set of which threads are looped to form the tuck, and the other sets of which are separated to form two continuous plies extending across under the tuck.

5 3. A woven tucked fabric the body of which is one ply between tucks, having three sets of warp-threads which are separated adjacent the tuck to form two plies each of which has weft-threads, and of which the facing has two sets 10 of said warp-threads and the backing one set,

and a tuck formed by looping one of the said facing sets.

In testimony whereof I have signed my name to this specification in the presence of two subscribing witnesses.

HARRY D. HEWETT.
